UNITED STATES PATENT OFFICE

HAROLD W. BROWN, OF SCHENECTADY, NEW YORK, ASSIGNOR TO GENERAL ELECTRIC COMPANY, A CORPORATION OF NEW YORK

MEANS FOR AND METHOD OF CONTROLLING THE CURRENT SUPPLY TO A LOAD CIRCUIT

Application filed December 22, 1927. Serial No. 241,942.

My invention relates to amplifiers and more particularly to a method and means for use in connection with amplifiers for controlling the supply of current to a load circuit which is supplied by an amplifier.

Devices are now known whereby the output from an amplifier to a load circuit may be maintained substantially constant independently of variations in the magnitude of the current supplied to the input of the amplifier circuit. These devices comprise means for varying the amplification characteristics of the amplifier in response to the intensity of the input currents.

In accordance with my present invention I provide a method and means for maintaining the supply of currents to a load circuit, which is supplied by an amplifier, substantially independent of variations in the amplification characteristics of the amplifier itself. In its broader aspects my invention comprises the idea of creating a plurality of paths connected between the supply circuit and the load circuit, and in controlling the supply of current through certain of said paths in response to variations in the transmission characteristics of other of said paths.

The novel features which I believe to be characteristic of my invention are set forth in the appended claims. My invention itself, however, both as to its organization and method of operation, together with further objects and advantages thereof, may best be understood by reference to the following description taken in connection with the accompanying drawing, which shows one embodiment of my invention.

Referring to the drawing, 1 and 2 represent electron discharge devices, each of which is connected to supply currents from a supply circuit 3 to a load circuit 4. Each of these devices comprises a grid, an anode and a cathode. The supply circuit 3 is connected between the grid and the cathode of the device 1 and the load circuit 4 is connected between the anode and the cathode of the device 2. 5 represents a transformer having a primary winding 6 and a secondary winding 7. The primary winding 6 of this transformer is connected in series with the

output of the device 1 and the load circuit 4. The secondary winding 7 of this transformer is connected in series between the supply circuit 3 and the input of the device 2, the arrangement being such that the potential between the terminals of the secondary winding 7 is in series opposed relation with the potential of the supply circuit 3. The ratio of transformation of the transformer 5 is substantially equal to the inverse of the normal amplification ratio of the electron discharge device 1, and such that the voltage across the winding 7 is proportional to the current flowing in the anode circuit of the device 1. 8, 9, 10 represent a suitable impedance network, which may comprise a single resistance 8 or suitable combination of resistance inductance and capacity, such as 8, 9, 10 which is connected in circuit with the primary winding 6 of the transformer 5, for the purpose of causing the voltage across the secondary winding to be in phase with the primary current. In the form shown, this impedance combination comprises a resistance connected in parallel with the primary winding of value such that it carries a substantial portion of the anode current of device 1 together with suitable inductance 9 and capacity 10 whereby the phase relation between the secondary voltage and primary current may be adjusted to the desired value. 11 and 12 represent sources of potential for energizing the anode and cathode circuits respectively of the devices 1 and 2.

As thus arranged it will be seen that while normal amplification of the device 1 is taking place no potential will be impressed upon the grid of the device 2 since the potential of the winding 7 is in series opposed relation to that of the source 3 in the circuit of the grid and cathode of the device 2. Thus this path connecting the supply and load circuits is normally inactive. If the amplification ratio of the device 1, however, should diminish for any reason then the potential of the winding 7 would correspondingly diminish and a portion of the potential of the source 3 would become effective upon the grid of the device 2, with the result that sufficient current would be supplied to the load 4.

through the device 2 to compensate for the diminution resulting from the changed amplification characteristics of the device 1. Likewise if the amplification ratio of the device 1 should increase then the potential of the transformer 7 will be greater than that of the source 3 with the result that a portion of this potential will be effective upon the grid of the device 2. This potential, however, will be in substantially opposed phase relation to the current flowing through the load 4 from the device 1, with the result that it will cause a diminution of the current in the load sufficient to compensate for the increased amplification ratio of the device 1. Thus it will be seen that any effect upon the load 4 of changes in the amplification characteristics of the device 1 will be substantially compensated by currents from the device 2.

20. While in the particular embodiment of my invention shown there are represented only two paths connecting the supply circuit to the load circuit, these paths comprising electron discharge devices, it will of course be understood that my invention may be employed in connection with a greater number of paths and paths which are otherwise constituted as well.

While I have shown and described a single embodiment of my invention it will, of course, be understood that I do not wish to be limited thereto since many modifications both in the circuit arrangements and instrumentalities employed, may be made without departing from the spirit and scope of my invention as set forth in the appended claims.

What I claim as new and desire to secure by Letters Patent of the United States, is:—

1. In combination, a load, means for supplying current to said load, means for amplifying said current and separate means responsive to variations in the amplification characteristics of said amplifying means for supplying current to said load.
45. 2. In combination, a plurality of amplifying devices having a common output circuit with which they are connected in parallel, each of said devices having an input circuit and means for controlling the input to one of said devices in response to the ratio between the input and output from another of said devices.
50. 3. In combination, a supply circuit, a load circuit, a plurality of parallel amplification paths connecting said circuits and means for controlling the current through one of said paths in response to the variations in the amplification of another of said paths.
55. 4. In combination, a load circuit, a supply circuit, a plurality of electron discharge devices, each of said electron discharge devices constituting a uni-directional path from said supply circuit to said load circuit and means for varying the current through one of said electron discharge devices in response to the

current through another of said electron discharge devices.

5. In combination, a pair of electron discharge devices each of said devices having an anode, a cathode and a grid, a supply circuit connected between the grid and cathode of one of said devices, a load circuit connected between the anode and cathode of the other device, and a transformer having a primary winding connected in series with the anode of said first device and said load circuit and a secondary winding connected in series with the grid of said other device and said supply circuit whereby the grid supply to said other device is determined by the ratio between the input and output from said first device.

6. In combination, a load, means for supplying current to said load, means for amplifying said current, an electron discharge device having a grid, said device being connected between said supply means and said load in a path shunting said amplifying means and means for controlling said grid in response to the amplification characteristics of said amplifying means.

7. In combination, a load, a source of potential, means for amplifying said potential and for supplying said potential to said load, an electron discharge device having an output circuit including said load and an input circuit including said source of potential, additional means responsive to the output currents from said amplifying means for supplying to said input circuit a potential which is normally equal and opposite in phase to the potential of said source, said potential being variable in response to the magnitude of the currents from said amplifying means, thereby to control the supply of current to said load.

8. In combination, a load, a source of potential, means for amplifying said potential and for supplying said potential to said load, an electron discharge device having an output circuit including said load and an input circuit including said source of potential, a transformer having a primary winding connected in circuit with said load and said amplifying means and a secondary winding connected in said input circuit in series opposed relation with said source of potential, the transformation ratio of said transformer being equal to the inverse amplification ratio of said amplifier, whereby the output from said discharge device is controlled by the amplification characteristics of said amplifier.

9. In combination, a load circuit, a supply circuit, a normally active path connecting said circuits, a normally inactive path connecting said circuits and means for rendering said normally inactive path active in response to and proportional to changes in the transmission characteristics of said normally active path.

10. The method of controlling the supply

of current from a source to a load consisting in causing current to flow through a plurality of parallel paths between said source and said load and in varying the current through one 5 of said paths in response to variations in the transmission characteristics of another of said paths.

11. The method of rendering the supply of current to a load independent of the amplification characteristics of an amplifier connected between the source of said currents and said load consisting in causing an additional current to flow between said source and said load and in varying said current in response 15 to changes in the amplification characteristics of said amplifier.

12. The method for use where amplifiers are employed to supply current from a source of potential to a load to render the supply of current to said load substantially independent 20 of the amplification characteristics of the amplifiers, consisting in creating an electron discharge current separate from said amplifier, supplying both the output from said amplifier and said electron discharge current to said load, producing a potential which is variable both in direction and in magnitude 25 with the difference between the output from and the input to said amplifier and in controlling said discharge current in response to said potential whereby variations in said discharge current compensates for variations in the output from said amplifier.

In witness whereof, I have hereunto set 30 my hand this 20th day of December, 1927.
